CONTAINER OPENING DEVICE FOR USE ON
ENGINESOzro N. Wiswell, Los Angeles, Calif., assignor to
Norman N. Wiswell, Los Angeles, Calif.

Application June 28, 1933, Serial No. 678,961

23 Claims. (Cl. 184—105)

This invention relates to devices for opening sealed containers and relates more particularly to container opening devices for use on the lubricating oil receivers of engines. It is a general object of the present invention to provide a simple, practical and effective device for opening sealed containers for use on or for application to the lubricating oil receivers of engines, such as the engines of automotive vehicles, etc.

10 Another object of the invention is to provide a container opening device to be arranged on or provided on the oil receiver of an engine that is adapted to cut a large, clean, substantially unobstructed opening in a container to allow its 15 contents to quickly and freely drain into the receiver.

Another object of the invention is to provide a device for opening sealed containers that is mounted on or carried by the oil filling pipe or 20 oil receiver of an engine that is adapted to support a container in a tipped or inclined position at the upper end of the receiver after being opened, with the opening formed by the device in its lowermost corner to allow the entire 25 contents of the container to quickly and completely drain into the receiver.

It is another object of the invention to provide a device for opening sealed containers that is carried by or mounted on the oil receiver of an 30 engine that does not interfere with the draining or pouring of oil into the receiver, or with the breathing of the engine.

It is another object of the invention to provide a container opening device for use on the oil receiving pipe or receiver of an engine that is normally disposed in the receiver where it is concealed and protected and that is shiftable to a 35 position where it is accessible and ready for use.

Another object of the invention is to provide a 40 device for opening sealed containers that is carried on the under side of the cover or cap on the oil receiver of an engine and is automatically positioned for use when the cover is opened.

Another object of the invention is to provide a 45 device for opening containers that is normally housed in an extension of the oil receiving pipe or oil receiver of an engine where it is protected and kept clean, and that is readily shiftable to an operative position where it projects from the 50 upper end of the receiver extension.

A further object of the invention is to provide a 55 container opening device for use on the oil receiving fitting or oil receiver of an engine that may be in the form of a simple, compact attachment adapted to be readily applied to the re-

ceiver or that may be in the nature of a part or element of the receiver structure built on the receiver as initially constructed.

A still further object of the invention is to provide a container opening device for use on the oil receivers of automotive engines and the like, that is simple and inexpensive of manufacture and that is easy and convenient to use.

Other objects and features of the invention will be better and fully understood from the following detailed description of typical forms and applications of the invention, throughout which description reference is had to the accompanying drawings, in which:

Fig. 1 is a vertical detailed sectional view of 15 one embodiment of the invention on the oil receiver of an engine illustrating a portion of the engine and showing a part of the receiver in elevation.

Fig. 2 is a vertical detailed sectional view of 20 the device illustrated in Fig. 1 illustrating the cover in the opened position where the cutter is accessible for use.

Fig. 3 is a fragmentary vertical detailed 25 sectional view taken as indicated by line 3—3 on Fig. 1.

Fig. 4 is a vertical detailed sectional view of 30 another form of the invention illustrating the cover or cap in the closed position.

Fig. 5 is a view similar to Fig. 4 illustrating 35 the cover in the open position and the cutter in the extended or operative position.

Fig. 6 is a transverse detailed sectional view 40 taken substantially as indicated by line 6—6 on Fig. 5.

Fig. 7 is a vertical detailed sectional view of 45 still another embodiment of the invention showing the cover in the closed position.

Fig. 8 is a view similar to Fig. 7 showing the cover in the open position and the cutter in the 50 projected operative position.

Fig. 9 is a vertical detailed sectional view of 55 still another embodiment of the invention illustrating the cover in the open position where the cutter is accessible for use.

Fig. 10 is a longitudinal detailed sectional view of 60 still another form of the invention illustrating the cap in its closed position and showing the cutter in an inverted position within the body or receiver.

Fig. 11 is a view similar to Fig. 10 with the cap 65 removed and the cutter in a righted and operative position where it projects from the receiver.

Fig. 12 is a vertical detailed sectional view of 70 still another form of the invention showing the 75

cover in the closed position and the cutter in the retracted position within the body.

Fig. 13 is a view similar to Fig. 12 showing the cover in the open position and the cutter in the 5 projected operative position.

Fig. 14 is a fragmentary transverse detailed sectional view taken substantially as indicated by line 14—14 on Fig. 12.

The present invention is capable of embodiment in forms for use on the oil filling or oil receiving pipes of engines of various characters and may be embodied either in the form of attachments or original features or parts of the engine structures. Throughout the following detailed 10 description of the invention I will disclose several typical embodiments used on the oil receiving pipes as found in the various types of automotive engines which forms may be considered as appliances or attachments, or as devices or parts provided on the engines as originally constructed. It is to be understood that the present invention is not to be construed as limited to the specific forms or applications about to be described, but that it is to be taken as including any features 15 or modifications that may fall within the scope of the claims.

The embodiment of the invention illustrated in Figs. 1, 2, and 3 of the drawings includes, generally, a body 10 forming a part of or a continuation 20 of the oil receiving pipe 11 of an engine E, a cover 12 for the upper end of the body 10, and a cutter 13 carried by the cover 12 and operable to open sealed containers.

The body 10 is a tubular member constituting 25 a continuation of the upper end portion of the oil receiving pipe and breather pipe of the engine E. The lower end of the fitting or pipe 11 communicates with the interior of the engine. In the particular engine structure illustrated in the 30 drawings, the receiver or pipe 11 has its lower end held in or received by an angular tubular boss 14 projecting from the body of the engine. The pipe 11 is vertical, it being understood that the form of the invention being described is capable of use 35 in connection with tilted or inclined receiver and breather pipes. The body 10 projects upwardly from the upper end of the pipe 11, and in accordance with the broader aspects of the invention, may be applied to or attached to the pipe portion 40 of the receiver in any suitable manner. In the particular case illustrated, the body 10 has a lower cylindrical portion 15 tightly fitting into the upper end of the pipe 11 that may be rigidly attached to the pipe if found necessary or desirable. 45 The body 10 flares outwardly and upwardly so that its major upper portion 16 is considerably larger in diameter than the portion 15 and pipe 11. The upper edge of the body 10 may lie in a 50 plane substantially normal to the longitudinal axis of the body and may be slightly turned outwardly or rolled.

The cap or cover 12 normally extends across 55 the open upper end of the body 10 to prevent objects and foreign material from entering the receiver. The cover 12 carries the cutter 13 and operates to clean or filter the air breathed by the receiver during operation of the engine. In the form of the invention being described, the cover 12 is hinged or pivoted to the upper end of the 60 body 10 so that it may be swung from the closed position illustrated in Fig. 1 to the open position illustrated in Fig. 2. The cover 12 includes a main body part or disc 17 adapted to seat on the upper edge of the body 10. The cover disc 17 65 is hingedly connected with the upper end portion

of the body 10 by a pivot pin or hinge pin 18 passing through openings in lapping or meshing parts of the disc and body. The disc 17 is provided with a stop 19 at its hinge connection to limit the outward swinging of the cover and to hold the cover in the inclined position illustrated in Fig. 2. The stop 19 is adapted to cooperate with the exterior of the body 10 upon the cover reaching the fully open inclined position to stop further opening movement. A spring finger or clip 20 is 10 provided on the disc 17 at a point diametrically opposite the hinge connection to engage under the rolled upper end of the body to releasably hold the cover in its closed position. The disc 17 is 15 perforated, being provided with a multiplicity of spaced openings 21.

The cover 12 may include an air filtering or straining means. A cup 22 is attached to the under side of the disc 17 and holds or carries a suitable air filtering material 23 such as steel wool, or the like. A plurality of spaced openings or perforations 24^a is provided in the bottom or under-side of the cap 22. A deflector plate 24 may be provided on the upper side of the cover 12 to laterally deflect the oil laden and smoke 25 fumes from the engine and to prevent the entrance of water or foreign material into the receiver. The plate 24 is attached to the disc 17 by a rivet 25 and is spaced from the disc 17 by a spacer 26 on the rivet. The peripheral portion 30 of the plate 24 is rolled or turned down to the disc 17 and is notched or perforated to admit and pass air.

The cutter 13 is attached to the under side of 35 the cover 12 to be housed within the body 10 when the cap is in its closed position and to be exposed and accessible for use when the cover 12 is in its opened position illustrated in Fig. 2 of the drawings. The cutter 13 is formed so that it is operable to cut a large clean opening in an end of a 40 container pushed or forced on to it, and is positioned on the under side of the cover 12 so that the contents of the container may drain directly into the body 10. In the preferred construction, the cutter 12 is substantially U-shaped in transverse cross section having two spaced side parts 45 27 joined by a transversely curved connected part 28. The cutter 13 is comparatively long but is proportioned so that it is freely received by the enlarged upper portion 16 of the body when the cover 12 is in the down or closed position. The connecting part 28 of the cutter is connected adjacent one end to the under side of the cup 22. In the particular case illustrated, the cutter is attached to the cup 22 by spaced rivets 29. A 50 spacer 30 is provided to space the connecting portion 28 of the cutter from the under side of the cup in parallelism with the under side of the cup. In accordance with the invention, the cutter 13 is attached to the under side of the cup 22 adjacent the periphery of the cup and adjacent to and in 55 diametric alignment with the hinge connection between the cover and the body 10. The cutter 13 extends diametrically across the under side of the cover 12 from its point of connection with the cover. The longitudinal edges 31 of the side parts 27 are pitched or inclined and converged to a point 32 at the outer or free end of the cutter. If desired, either one or both sides of the point portion of the cutter may be beveled. The inclined edges 31 are flat and substantially normal 60 to the side surfaces of the parts 27. Spaced drain openings 33 may be provided in the cutter 13 at points adjacent the inner end of the spacer 30. Means may be provided for releasably holding 65

the cover 12 in the open inclined position illustrated in Fig. 2 of the drawings. In practice, any suitable type of device may be employed to releasably hold the cover in the open position. In 5 the case illustrated in the drawings a releasable holding device 34 in the form of a flexible member is attached to the cover 12 adjacent its hinged connection with the body 10. The releasable holding device 34 is bent or curved to have its free 10 end pass through an opening 35 in the wall of the body 10 when the cutter 13 is moved to its open position. A bend or notch 36 is provided in the device 34 to receive an edge portion of the opening 35 and the flexible device 34 is formed so as to 15 spring or yield as its end enters the opening 35 to dependably hold the notch 36 in cooperation with the wall of the opening 35. Upon the cover 12 being shifted to its fully open position, the end of the releasable holding device 34 enters the 20 opening 35 and its notch 36 receives the edge portion of the opening to retain the cover in the open position. The device 34 may be released by bending it upwardly to disengage it from the wall of the opening 35.

25 It is believed that the utility and practicability of the form of the invention illustrated in Figs. 1 to 3 inclusive of the drawings will be readily apparent from the foregoing detailed description. The cover 12 is normally in its down or closed 30 position illustrated in Fig. 1 where the cutter 13 is fully housed within the enlarged portion 16 of the body 10. During operation of the engine E, air is free to pass in and out through the perforations in the disc 17 and cup 22 and is filtered 35 by the material 23. When it is desired to open a sealed container of oil and drain its contents into the receiver of the engine, the cover 12 is opened and swung to the fully open position where it is inclined as illustrated in Fig. 2 of the drawings.

40 The stop 19 and the releasable holding device 34 operate to hold the cover in this position. The container may then be pushed or forced down on the cutter 13 so that the point 32 of the cutter pierces an end of the container immediately adjacent 45 its peripheral edge. As the container is pushed down on the cutter 13 the space between the under side of the cup 22 and the part 28 of the cutter receives the adjacent wall of the container. In practice, the spacing of the cutter 13 from the under side of the cup 22 is such that the bead commonly provided on the peripheral edges of sealed containers is slidable between the opposing 50 surfaces of the cutter and cup. In this manner the under side of the cup 22 acts as a guide to 55 guide the container as it is pushed downward on the cutter 13. In practice, the point 32 of the cutter may be spaced inwardly from the periphery of the cup 22 so that the bead at the edge of the container may be brought against the under side 60 of the cup to be guided thereby as the container is advanced on to the cutter. The pointed end of the cutter pierces the end of the container adjacent its periphery and the outer longitudinal corners of the edges 31 cut or shear the end wall of 65 the container as it is pushed down on the cutter thus enlarging the cut inwardly. The flat edges 31 engage the flap outlined by the cut and roll it upwardly and outwardly, leaving the opening substantially unobstructed. The spacer 30 limits 70 the downward movement of the container on the cutter 13 and aids in supporting the container. When the cut has been made, the container is supported in an inclined position on the cutter 13 with the opening formed by the cutter in its low- 75 ermost portion directly over the open-mouthed

body 10 so that the contents of the container are free to drain into the body 10 and pipe 11. The cup 22 and spacer 30 space the cutter 13 inwardly so that the opened lower portion of the container is inwardly of the side wall of the body 10 to prevent the oil from splashing or falling outside of the body. The openings 33 in the cutter 13 allow the oil from the outside of the cutter to freely drain out through the opening formed in the end of the container. The container is supported on the cover and cutter so that the user does not have to hold it or steady it as it drains. After the contents have drained from the container, the container may be readily pulled upwardly and disengaged from the cutter. The releasable holding device 34 may then be released to allow the cover 12 to be returned to its closed position. The sealed containers of oil may be easily and quickly opened by the device and their contents directly drained into the receiver of the engine. The containers are dependably supported in an inclined position on the cutter to insure the draining of all of their contents into the receiver. The provision of the cutter 13 on the under side of the cover 12 does not in any way complicate 25 the structure or interfere with the breathing function of the receiver. When the cover 12 is in its opened position, the cutter 13 does not in any way interfere with the pouring of lubricant into the open end of the receiver. 30

The embodiment of the invention illustrated in Figs. 4, 5, and 6 of the drawings includes, generally, a body 40 forming a part of or adapted to be applied to the lubricant receiver 11a of an engine, a cap or cover 41 for the upper end of the body 40, and a cutter 42 in the body 40 operable to a position where it is adapted to open sealed containers after shifting of the cover 41 to an open position. 35

The body 40 is adapted to constitute an extension or continuation of the upper end of the receiver 11a. The invention contemplates either the rigid attachment of the body 40 to the receiver 11a or the applying of the body 40 to the receiver in any suitable manner. In the particular case illustrated in the drawings, the body 40 includes a flared or substantially inverted frustoconical major portion 43 and a cylindrical lower portion 44 fitted into the upper end portion of the receiver 11a. The upper edge of the body 40 may be horizontal or in a plane normal to the longitudinal axis of the body and may be rolled as illustrated. 40

The cap or cover 41 is pivotally attached to the body 40 so that it may be shifted between a closed 55 position over the upper end of the body and an open position out of vertical alignment with the upper end of the body. The cover 41 includes a substantially disc shaped member 45 proportioned to project beyond the upper edge of the body 40 when the cover is in the closed position. The peripheral edge portions of the member 45 are curved downwardly and a perforated disc shaped plate 46 is arranged at the lower peripheral edge of the disc 45 and is suitably attached to the disc. 60 The plate 46 is spaced below the main part of the disc 45 to provide a space for holding an air screening or filtering material 47. The peripheral portion of the plate 46 projects beyond the upper end of the body 40 and is perforated to allow for 65 the breathing of air through the filtering material 47 in the cover. A pivot pin 48 extends through an opening in the plate 46 and a block 49 on the upper edge portion of the body 40 to pivotally attach the cover to the body. A spring 70 75

50 may be provided to normally yieldingly hold the cover in proper engagement with the upper edge of the body.

The cutter 42 for opening the containers of oil 5 is mounted on the inner side of the main body portion 43 in a manner so as to be shiftable or operable between a position entirely within the body 40 and a position where it projects from the upper end of the body. In the embodiment of the 10 invention being described, the cutter 42 is pivotally attached to the body 40 so that it may be swung between the inoperative position in the body and the operative position where it projects from the upper edge of the body. The cutter 42 15 is substantially U-shaped in transverse cross section having spaced side parts 51 and a transversely curved connecting part 52. The longitudinal edges 53 of the side parts 51 are inclined and join at a point 54 at an end of the cutter. The 20 edges 53 are preferably flat and substantially normal to the side surfaces of the parts 51. Spaced drain openings 55 are provided in the cutter 42 adjacent its broad end.

A guide 56 is provided in conjunction with the 25 cutter 42 to guide containers on the cutter. The guide 56 is an elongate member spaced from and substantially parallel to the outer side of the cutter part 52. The guide 56 may be slightly curved in transverse cross section to effectively 30 guide cylindrical containers. A spacer 57 connects the broad or lower end of the cutter 42 with the guide 56. The cutter and guide may be welded to the spacer 57. The inner or lower end of the guide 56 is pivotally connected with the body 40. 35 A pivot pin 58 extends through openings in the guide 56 and a connecting member 59 on the inner wall of the body 40 to pivotally connect the cutter and guide with the body. The cutter and guide are pivotally mounted on the inner flaring wall of 40 the body 40 at a point spaced below the upper edge of the body and at a point substantially diametrically opposite the pivotal connection between the cover 41 and the body. The cover 41 is normally in its closed position where it seats 45 against the upper edge of the body 40 and operates to filter the air breathed by the engine.

When it is desired to pour the contents of a container of oil in the crank case of the engine, the cover 41 is swung to its open position and 50 the assembly of the cutter 42 and guide 56 is pivoted upwardly to the projecting position illustrated in Fig. 5 of the drawings. When the cutter 42 is in its projecting operative position, the outer side of the guide 56 bears against the inner 55 wall of the body 40 providing an effective support for the cutter in addition to its pivotal mounting. The bead B at the peripheral edge of the container C is brought into engagement with the inner surface of the guide 56 and the container 60 is pushed or forced downwardly on the inclined cutter 42 so the point 54 of the cutter pierces the end of the container. The guide 56 insures the engagement of the point 54 with the end of the container immediately adjacent its peripheral 65 bead B and downward movement of the container on the cutter causes the outer longitudinal corners of the edges 53 to cut or shear the container end, thus enlarging the opening inwardly. The force exerted on the container C when it is 70 opened on the cutter 42 is directed downwardly and inwardly toward the center of the body 40 so that it has no tendency to tip the assembly of the cutter and guide. The spacer 57 limits the downward movement of the container C and aids 75 in supporting the container on the cutter. The

engagement of the container with the guide and cutter and the engagement of the cutter with the walls of the opening it has formed in the container end effectively supports the container in the inclined position on the cutter. The contents 5 of the container are free to drain directly into the open mouth of the body 40 and flow into the crank case of the engine. The drain openings 55 allow the oil behind the cutter to entirely drain out of the container. As the container is effectively supported on the cutter the user is not forced to hold the container as it drains. After the container is entirely drained, it may be easily disengaged from the cutter and guide. The assembly of the cutter and guide may then be 10 pivoted to its down position within the body 40 and the cover 41 swung to its closed position over the upper end of the body.

The form of the invention illustrated in Figs. 7 and 8 of the drawings includes generally, a 20 body 60, a cap or cover 61 for the body, and a cutter 62 shiftable between a position within the body 60 and a position where it projects from the upper end of the body.

The body 60 is adapted to be attached to or to 25 form a part of the lubricant receiver 11^b of the engine and is a tubular member forming a continuation of the receiver. The body 60 includes a cylindrical lower portion 63 engaging or fitting into the receiver part 11^b and a major portion 64 30 that is laterally enlarged so as to be adapted to receive the lower portion of a tilted container. The walls of the laterally enlarged portion 64 of the body are inclined upwardly and outwardly. The upper end of the body 60 may be straight 35 and horizontal and may be rolled.

The cover 61 is pivotally attached to the body 60 so as to be operable between a position where it extends across the upper end of the body and a position where it is out of alignment with the 40 body opening. The cover 61 may be similar to the cover 41 described above, that is, it may be a hollow substantially disc-shaped structure filled with steel wool, or the like, 65. The lower wall of the cover 61 is perforated and overhangs the 45 upper edge of the body 60 to allow for the breathing of the engine through the receiver. A pivot pin 66 pivotally attaches the cover 61 with the upper edge portion of the body 60.

The cutter 62 is longitudinally shiftable or 50 movable between a position entirely within the body and a position where it projects from the upper end of the body. The cutter 62 is similar to the cutter 42 described above, being substantially U-shaped in transverse cross section. The 55 cutter 62 has two spaced side parts 67 and a transversely curved connecting part 68. The longitudinal edges 69 of the side parts 67 are inclined upwardly and outwardly and converge to join at a point 70 on the upper end of the 60 cutter. The edges 69 are preferably flat and substantially normal to the side faces of the parts 67. Spaced drain openings 71 may be provided in the broad end portion of the cutter. A guide 72 is provided in connection with the cutter 62 65 for carrying the cutter and for guiding the containers on to the cutter. The guide 72 is spaced from and substantially parallel with the curved outer portion 68 of the cutter and is connected with the cutter by a spacer 73. The spacer 73 70 may be welded to the lower end portion of the guide 72 and the lower end portion of the cutter part 68. The guide 72 extends upwardly beyond the pointed upper end of the cutter. In accordance with the invention, the guide 72 has sliding 75

bearing engagement with the upwardly and outwardly inclined wall of the enlarged body portion 64 and constitutes a carrier for the cutter, carrying or supporting the cutter for movement between its position in the body and its position projecting from the body. A slidable connection is provided between the assembly of the cutter and guide and the body 60. A longitudinal slot 74 is provided in the guide 72 and slidably receives a pin or rivet 75 projecting inwardly from the inclined wall of the body 60. The inner head of the rivet 75 engages the inner side of the guide 72 to retain the guide in proper sliding bearing engagement with the inner wall of the body 60.

15 It will be apparent how the assembly of the cutter 62 and guide 72 are shiftable or slidable on the inclined wall of the body between the position illustrated in Fig. 7 of the drawings and the projecting operative position illustrated in Fig. 8 of the drawings.

20 Means is provided for releasably supporting or holding the assembly of the cutter 62 and guide 72 in its projecting operative position. A latch or stop 76 is carried by a spring arm 77 and is adapted to be engaged by the lower end of the guide 72. The stop 76 is adapted to project through an opening 78 in the inclined wall of the body 60, and when in this position, is engageable by the lower end of the guide 72 to support the assembly of the guide and cutter 62 in its up or projecting position. The spring arm 77 normally yieldingly urges the stop 76 inwardly so that when the cutter 62 is shifted to the up or projecting position, the stop 76 is automatically moved inwardly to be engaged by the lower end of the guide 72. A suitable handle 79 may be provided on the spring arm 77 so that the stop 76 may be easily moved outwardly when it is desired to shift the cutter 62 down to its position within the body. In the construction illustrated in the drawings, the rivet 75 operates to attach the spring arm 77 to the body.

25 The cover 61 is normally in its closed position over the upper end of the body 60, and the cutter 62 and guide 72 are normally disposed within the body. When oil from a sealed container is to be poured into the crank case of the engine the cover 61 is swung to its open position and the assembly of the cutter 62 and guide 72 are shifted or slid upwardly on the inclined wall of the enlarged body portion 64 to the up position illustrated in Fig. 8 of the drawings. When the guide and cutter reach this position, the stop 76 automatically moves inwardly under the guide to support the guide and cutter in the projecting operative position. The peripheral bead of one end of the container is positioned against the projecting upper end part of the guide 72 and the container is forced downwardly on the cutter 62.

30 The point 70 on the upper end of the cutter pierces the end of the container immediately adjacent its periphery and the longitudinal outer corners of the edges 69 shear or cut the end of the container as the container is forced down on the cutter providing a large substantially unobstructed opening in the end of the container. The flat edges 69 roll back the flap outlined by the cut so that it does not interfere with the draining of the contents from the container. The container is supported in a tilted or inclined position on the cutter after the cut has been made so that its entire contents are free to drain out into the body 60 and receiver 11b. As the lower end of the tilted container is disposed within the flaring or enlarged portion 64 of the body,

the entire contents of the container are received by the body and are prevented from splashing or over-flowing from the upper end of the body. After the oil has drained from the opened container, the container may be easily disengaged from the cutter and guide, and the stop 76 may be pulled outwardly so that the guide and cutter may be slid down to the inoperative position within the body. The cover 61 may then be swung to its closed position. The cutter 62 is always available for use and may be easily and quickly shifted to its operative position after the cover 61 has been swung to the open position. The cutter and guide do not interfere with the pouring of oil into the receiver and are normally entirely concealed and protected by the cover 61.

10 The embodiment of the invention illustrated in Fig. 9 of the drawings includes a body 80 forming a part of or adapted to be applied to the oil receiver 11c of an engine and adapted to receive the end portion of a container of oil, a cover 81 for the body 80, and a cutter 82 mounted within the body 80 for opening a container pushed into the body.

15 The body 80 may be provided on or applied to the main part of the receiver 11c in any suitable or practical manner. In the particular case illustrated in the drawings, the body 80 includes a tubular lower portion 83 of circular cross section received in the upper end portion of the receiver part 11c. The body 80 has an enlarged upper portion 84 proportioned and shaped to receive a part of a tilted or inclined container. The enlarged portion 84 of the body is preferably partially cylindrical in transverse cross section to receive cylindrical containers, and its axis is inclined relative to the longitudinal axis of the receiver 11c. The upper end of the body 80 may be straight and substantially horizontal. The cap or cover 81 may be similar to the covers 41 and 61 described above. In the case illustrated in the drawings, the cover 81 is pivotally attached to the body 80 as at 85 so that it may be swung between the closed position and the open position.

20 In accordance with the embodiment of the invention illustrated in Fig. 9 of the drawings, the cutter 82 is mounted on or attached to the interior of the body 80. The cutter 82 is mounted on the interior wall of the enlarged body portion 84 so as to open a container that is forced or pushed on it. The cutter 82 is similar to the cutters 42 and 62 described above, being substantially U-shaped in transverse cross section to have spaced side parts 86 and a transversely curved connecting part 87. The longitudinal edges 88 of the side parts 86 are inclined and converge to a point 89 at the upper end of the cutter. Spaced drain openings 90 may be provided in the broad end portion of the cutter. The cutter 82 is attached to or mounted on the inner lower wall of the enlarged body portion 84. In the construction illustrated, the lower end part of the cutter 82 is attached to a spacer 91 on the inner wall of the enlarged body part 84. The cutter 82 is preferably attached to the lowermost portion of the interior wall of the body part 84. The spacer 91 supports the cutter 82 in a position where its portion 87 is spaced from and parallel to the inclined wall of the body portion 84.

25 In the operation of the form of the invention illustrated in Fig. 9 of the drawings, the cover 81 is swung to the open position when it is desired to open a container and drain its contents into the engine. The container held in a tilted position, is slid downwardly on the inclined wall of

75

the body portion 84 so that the point 89 of the cutter pierces its lower end immediately adjacent its periphery. The wall of the enlarged body portion 84 forms an effective guide for the container as it is forced on to the cutter. The outer longitudinal corners of the edges 88 operate to enlarge the cut inwardly in the end of the container and bear against the flap outlined by the cut causing it to be rolled inwardly. The contents 10 of the container are free to entirely drain out through the opening formed by the cutter and drain directly into the receiver. After the contents have drained from the container, the container may be easily disengaged from the cutter 82 and removed from the body whereupon the cover 81 may be swung to its closed position.

The form of the invention disclosed in Figs. 10 and 11 of the drawings includes generally, a body 95 on or forming a part of the lubricant receiver 20 of an internal combustion engine, a strainer cap or filtering cap 96 for the body and a cutter 97 removably seated within the body 95 adapted to be removed from the body and reseated therein in an operative position where it projects from the body to open a container pushed down upon it.

The body 95 may be suitably attached to the receiver 11^d or may constitute a part of the receiver as initially constructed. In the particular form of the invention being described, the body 30 95 has a reduced lower portion 98 fitting within the upper end part of the receiver 11^d and attached thereto by rivets 99. The tubular body 95 has a flared portion 100 extending outwardly from the portion 98 and an outer cylindrical portion 101. In the particular case illustrated, the receiver is inclined and the longitudinal axis of the body is correspondingly inclined. The upper end of the body 95 may be straight and in a plane normal to the longitudinal axis of the body.

40 The cap 96 is removably arranged on the outer end part of the body 95 to filter the air breathed by the engine. The cap 96 includes a tubular shell 102 slidably fitting on the body part 101 and a disc 103 closing the outer end of the shell. A 45 row of perforations or openings 104 is provided in the shell and screening 105 extends across the opening in the shell below the row of perforations 104. The screening 105 may have a flange fitting over the row of openings 104. The disc 103 has 50 an inturned peripheral flange 106 overhanging the row of openings 104. It will be apparent how the screening 105 effectively filters or screens the air and how the flange 106 prevents the entrance of foreign matter into the openings 104. The cap 55 96 is easily removed from the body.

The cutter 97 is normally mounted within the body 95 in an inverted position and is removable from the body so that it may be righted or turned to an upright position and re-seated in the body 60 so that it projects upwardly from the body to be operable to open a container forced down upon it. The cutter 97 is substantially U-shaped in transverse cross section having two spaced side parts 109 and a transversely curved connecting part 65 110. The longitudinal edges 111 of the side parts 109 converge to a point 112 on the upper end of the upright or righted cutter. Feet or mounting flanges 113 are provided on the lower ends of the side parts 109. Drain openings 114 extend 70 upwardly from the lower ends of the side parts 109 and are separated by a tongue 115 forming a continuation of the curved connection part 110. The edges 111 are preferably flat and normal to the side surfaces of the parts 109 to effec- 75

tively shear the end of the container during the cutting operation.

The cutter 97 is carried by a carrier 115 removably seated in the body 95. The carrier 115 includes a ring 116 adapted to slidably fit in the outer portion 101 of the body and a web 117 extending across the opening of the ring. When the carrier 115 is positioned in the body, one of its ends is adapted to engage or seat on the shoulder 118 formed by the internal wall of the 10 frustro-conical body portion 100. The web 117 is provided to support the cutter 97 and is perforated, having comparatively large spaced openings 120. The flanges 113 are seated on the web 117 and are suitably attached to the web. In 15 the case illustrated in the drawings, the flanges 117 are welded to the web. In accordance with the invention the legs 113 are angularly related to the body of the cutter 97 to support the cutter on the web 117 so that it is inclined upwardly and 20 outwardly when in its operative position. The cutter 97 is preferably substantially centrally disposed on the web 117. One or more of the openings 120 in the web are in direct register or communication with the draining openings 114 of 25 the cutter. A guide 121 is provided on the web 117 to guide the containers on to the cutter 97. The guide is provided at its lower end with a laterally projecting mounting flange 122 attached to the web 117. The body of the guide 121 is 30 spaced from and is substantially parallel with the connecting part 110 of the cutter. The guide 121 preferably projects beyond the point 112 of the cutter.

The carrier 115 is normally positioned in the 35 body 95 so that the cutter 97 is on its underside and projects downwardly through the body. The cap 96 is normally mounted on the body 95 to prevent the entrance of foreign material to the receiver. When it is desired to open a container 40 of oil and drain its contents into the lubricant receiver of the engine, the cap 96 is removed from the body 95 and the carrier 115 is taken out of the body. The carrier 115 is disposed in the upper part of the body and is always easily engageable 45 for removal. After the carrier 115 has been removed from the body it is inverted to right the cutter 97 to an upright position and is then returned to the body 95 to support the cutter 97 in the upstanding position illustrated in Fig. 11 50 of the drawings. The container may then be forced or pushed downwardly on the cutter to be opened thereby so that its contents may drain into the receiver. The point 112 of the cutter operates to pierce the end of the container immediately adjacent its periphery and the edges 55 111 enlarge the opening, as the container moves downwardly, and rolls back the flap outlined by the cut leaving a substantially unobstructed opening in the end of the container. The guide 121 60 effectively guides the container as it is being opened. The cutter 97 and guide 121, in being inclined support the opened container in an inclined or tipped position with the opening in its lower end at the lowest point so that the entire 65 contents quickly drain from the container. The openings 120 in the web allow the oil to freely drain into the receiver. After the contents have drained from the container the container may be disengaged from the cutter and guide, whereupon the carrier 115 may be removed from the body and turned over so that the cutter is in an inverted position. The carrier 115 is returned to the body and seated in its original position and the cap 96 is placed on the upper end of the 70 75

body. The container opening cutter 97 is removably seated or positioned in the body 95 in a manner so that it is convenient and accessible for use when it is desired to open a container of oil. The cutter in being positioned directly over the opening of the body forms an opening in the end of the container which allows the entire contents to drain out without loss or leakage.

The embodiment of my invention illustrated in Figs. 12, 13, and 14 of the drawings includes, generally, a body 150 on or forming a part of the oil receiver 11^e of an internal combustion engine, a cap or cover 151 for the body, and a cutter 152 mounted in the body 150 for longitudinal movement between a position entirely within the body and an operative position where it projects from the upper end of the body.

The body 150 which forms an extension or continuation of the lubricant receiver 11^e of the engine may be mounted on or attached to the receiver in any suitable or desirable manner. The particular body 150, illustrated in the drawings, is an elongate tubular member having a reduced lower portion 153 fitting into the upper end portion of the receiver part 11^e. The body 150 flares upwardly and outwardly from the upper end of the part 153 and has a main enlarged upper portion 154 with cylindrical internal and external walls.

30 The cover 151 may be in the nature of any suitable air filtering means for the upper end of the body 150. In the particular application of the invention being described, the cover 151 is similar to the covers 41 and 61 described above, being a substantial disc shaped hollow member filled with steel wool, or the like. The lower wall of the cap or cover 151 is provided with a plurality of openings 156 and over-hangs the upper end of the body to allow for the passage of air into and 40 out of the receiver. A pivot pin 157 pivotally connects the cover 151 to the body so that it may be swung between the open and closed positions.

The cutter 152 is supported in the enlarged upper portion 154 of the body for longitudinal movement between a position where it is entirely within the body and an operative position where it projects from the upper end of the body. The cutter 152 is similar to the cutter 97 described above, being substantially U-shaped in cross section. The two side parts 158 of the cutter are parallel and in substantial vertical planes, while the curved connecting part 159 of the cutter is inclined upwardly and outwardly. The longitudinal edges of the side parts 158 are inclined upwardly and outwardly and converge to a point 161 at the upper end of the cutter. Drain openings 162 are provided in the lower end portions of the side parts 158 and are separated by a tongue 163 which is a continuation of the connecting portion 159. The lower end of the tongue 163 may be curved or bent inwardly as illustrated in the drawings. Inwardly projecting feet or flanges 164 are provided on the lower ends of the side parts 158 of the cutter.

65 The cutter 152 is supported by a vertically or longitudinally shiftable carrier comprising a ring 165 and a web 166 in the ring. The ring 165 is shiftable or slidable longitudinally in the enlarged upper portion 154 of the body between 70 the position illustrated in Fig. 12 and the position illustrated in Fig. 13. The web 166 is attached to the ring 165 and is substantially disc-shaped to fit the opening in the ring. In accordance with the invention, the web 166 is provided 75 with a plurality of spaced openings 167. The

flanges 164 on the lower end of the cutter 152 are seated on the upper side of the web 166 and are attached to the web in any suitable manner. In the particular case illustrated, the flanges 164 are attached to the web by welding. The flanges 164 are preferably attached to the upper side of the web 166 at or adjacent its center. The flanges 164 are related to the body parts of the cutter 152 so that the cutter projects upwardly and outwardly from the surface of the web 166. A guide 168 is provided for guiding the containers on the cutter 152. The guide 168 may be curved in transverse cross section and is mounted on the upper side of the web 166 so as to be spaced from and substantially parallel to the outer surface of the cutter part 159. The guide 168 projects upwardly beyond the upper end of the cutter 152 and is provided at its upper end with an outwardly projecting extension or tongue 170. The tongue 170 is adapted to engage the upper end of the body 20 150 to support the cutter and carrier when they are in the down position entirely within the body. A notch 171 may be provided in the upper edge of the body 150 to receive the tongue 170.

25 Means is provided for guiding the cutter carrier for longitudinal movement in the body 150 and for supporting the carrier when the cutter is in the operative position. A plurality of circumferentially spaced longitudinal keys 172 is provided on the interior walls of the enlarged body 30 portion 154 for cooperating with key-ways 173 in the carrier ring 165. The keys 172 terminate at points spaced below the upper end of the body 150 and the cutter carrier is shiftable upwardly so that its key ways 173 may be disengaged from the 35 keys whereupon the carrier may be turned so that the lower end of the ring 165 is supported on the upper ends of the keys 172 so that the cutter 152 projects from the upper end of the body.

40 It is believed that the operation of the embodiment of the invention illustrated in Figs. 12, 13, and 14 of the drawings will be understood from the foregoing detailed description. The cutter 152 is normally entirely within the body where 45 the tongue 170 supports the assembly of the cutter guide and cutter carrier in the body. When it is desired to open a sealed container of lubricating oil and drain its contents into the crank case of the engine, the cover 151 is swung to the open position so that the projecting tongue 170 which may serve as a handle may be engaged for shifting the assembly of the cutter, guide, and cutter carrier upwardly in the body. When the ring 165 of the cutter carrier reaches the upper 50 end portion of the body where its key ways 173 are disengaged from the keys 172, it may be turned so that its lower end may engage the upper ends of the keys to support the carrier and cutter in the up position. The cutter 152 and 55 the guide 168 then project from the upper end of the body 150 so that a container may be pushed downwardly on the cutter to be opened. In opening the container, the bead at its lower end is arranged against the inner surface of the projecting portion of the guide 168 and the container is pushed downwardly so that the point 161 of the cutter pierces its lower end immediately adjacent its periphery. The outer longitudinal corners of the edges 160 operate to cut or shear 70 the end wall of the container as the downward movement of the container continues, thus enlarging the opening. The edges 160 are preferably flat so that they engage the flap outlined by the cut to roll it back out of the opening formed 75

by the cutter. As the guide 168 and the outer portion 159 of the cutter are inclined, the container when opened and supported on the cutter and guide is also inclined and has the opening 5 formed by the cutter in its lowermost part. The oil is free to drain from the opening made by the cutter and discharges through the openings 167 directly into the lubricant receiver of the engine. As the container is tipped or inclined when opened 10 and supported on the cutter, its entire contents are free to quickly drain into the receiver. The drain openings 162 in the cutter allow the free drainage of oil from behind the cutter. After the contents have completely drained from the 15 container the container may be removed or disengaged from the cutter and guide so that the assembly of the cutter guide and cutter carrier may be returned to its normal position in the body. To return the assembly to its down or 20 normal position, the assembly is turned so that the tongue 170 is in vertical alignment with the notch 171 in which position the key ways 173 register with the keys 172 and receive the keys allowing the assembly to be moved downwardly in 25 the body. The tongue 170 is received by the notch 171 in the upper end of the body and is effectively retained in the notch by the cover 151. The container opening cutter 152 of the device is 30 normally concealed and protected within the oil receiver of the engine but is at all times accessible for use. The cutter may be quickly shifted to its up or operative position and the containers may be quickly opened by the cutter so that their contents may completely drain directly into the 35 lubricant receiver of the engine.

Having described only typical forms and applications of my invention, I do not wish to be limited or restricted to the specific forms and applications set forth, but wish to reserve to myself 40 any modifications or variations that may appear to those skilled in the art or fall within the scope of the following claims:

Having described my invention, I claim:

1. A conduit for conducting the lubricant into 45 an engine characterized by a cutter shiftable from a position within the conduit to a position projecting upwardly from its receiving end where it is operable to open a container of lubricant to drain into the conduit.

2. A device for use on the tubular lubricant receiver of an engine including, a pivoted cover on 50 the outer end of the receiver, and a cutter on the under side of the cover extending substantially parallel with the under surface of the cover to 55 open a sealed container moved along said surface and brought into engagement with it when the cover is in an open position.

3. A device for use on the tubular lubricant receiver of an engine including, a shiftable cover 60 on the receiver movable from a position where it extends across the outer end of the receiver to an open position clear of the opening in the outer end of the tubular receiver, and a cutter normally under the cover and projectible from 65 the outer end of the receiver for engagement by a container when the cover is in its open position.

4. A device for use on the tubular lubricant receiver of an engine including, a cover pivoted on 70 the receiver to be movable from a position where it extends across the outer end of the receiver to an open position where it is inclined downwardly and inwardly relative to the open upper end of the receiver, releasable means for holding the cover in the open position, and a cutter carried 75 on the under side of the cover operable to open

a container brought into engagement with it when the cover is in the open position.

5. A device for use on the lubricant receiving pipe of an engine including, a tubular body adapted to be applied to the pipe to form a continuation thereof, a cover on the body operable between a closed position and an open position, and a cutter on the under side of the cover operable to open a container forced downwardly upon it when the cover is in the open position, the 10 under side of the cover having a surface operable to guide the container as it is opened on the cutter.

15 6. A device for use on the lubricant receiving pipe of an engine including a tubular body adapted to be applied to the pipe to form a continuation thereof, a cover pivoted on the body to be operable between a closed position and an open position, and a cutter on the under side of the cover operable to open a container forced upon 20 it when the cover is in the open position, and to thereafter support the container in an inclined position and with its lower end over the open upper end of the body and spaced from the wall 25 of the body.

7. A device for use on the tubular lubricant receiver of an engine including, a cutter pivoted in the receiver to be operable between a position in the receiver and a position where it projects from the receiver to open a container 30 brought into engagement with it.

8. A device for use on the tubular lubricant receiver of an engine including, a cover on the receiver movable between a position over the end of the receiver and an open position, and means 35 for opening containers including a cutter, and a guide connected with and having a part spaced from the cutter for guiding a container on the cutter, and means mounting the cutter and guide on the receiver to be operable between a position 40 in the receiver and a position projecting from the end of the receiver.

9. A device for use on the tubular lubricant receiver of an engine including, a cutter adapted to open a container brought into engagement 45 with it, and a guide connected with the cutter to guide a can onto the cutter, the guide being shiftable on the receiver whereby the cutter and guide are movable between a position in the receiver and a position projecting from the receiver. 50

10. A container opening device for use on the lubricant receiving pipe of an engine including a body adapted to be positioned on the pipe, a cutter operable to cut an opening in a container pushed onto it, a member for guiding the container on the cutter, the member carrying the cutter and being shiftable on the interior of the body between a position where the cutter is in the body and a position where the cutter projects from the end of the body, and means for guiding 55 the member for such movement.

11. A container opening device for use on the lubricant receiving pipe of an engine including a body adapted to be positioned on the pipe, a cutter movable in the body between a position in the 60 body and a position projecting from the body where it is adapted to cut an opening in a container pushed against it, and a shiftable cover for the body.

12. A container opening device for use on the 70 lubricant receiving pipe of an engine including a body adapted to be positioned on the pipe, a cutter shiftable to cut an opening in a container pushed onto it, a member for guiding the container on the cutter, the member carrying the 75

5 cutter and being shiftable on the interior of the body between a position where the cutter is in the body and a position where the cutter projects from the end of the body, and releasable means for supporting the member in the last named position.

10 13. A container opening device for use on the lubricant receiving pipe of an engine including a body adapted to be positioned on the pipe, a shiftable cover for the outer end of the body, and a pivoted cutter on the body shiftable between a position in the body and an inclined position projecting from the body where it is adapted to cut an opening in a container moved 15 into engagement with it.

14. A device for use on the lubricant receiver of an engine, including a member shiftable in the receiver from an in position within the receiver to an out position where it projects from 20 the receiver, a cutter on the member adapted to project from the end of the receiver when the member is in the out position and entirely housed in the receiver when the member is in an in position, and means for supporting the member 25 in said out position.

15. A device for use on the lubricant receiving pipe of an engine including, a tubular body adapted to be applied to the pipe to form a continuation thereof, a cutter operable to cut an 30 opening in a container forced onto it, a member supporting the cutter and movable in the body between a position where the cutter is in the body and a position where the cutter projects from the body and is operative, and means for supporting the member in the last mentioned position.

16. A device for use on the lubricant receiving pipe of an engine including, a tubular body adapted to be applied to the pipe to form a continuation thereof, a cutter operable to cut 40 an opening in a container forced onto it, a member supporting the cutter and movable in the body between a position where the cutter is in the body and a position where the cutter projects from the body and is operative, a guide on 45 the member for guiding a container on the cutter, and means for supporting the member in the last mentioned position.

17. A tubular oil receiving member of an engine, and means movable from a position in the 50 member to a position projecting upwardly from

the receiving end of the member for cutting an opening in the lower end of a container so that its contents may drain directly into the member.

18. A conduit for conducting the lubricant into an engine characterized by a cutter shiftable from a position in the conduit to an inclined position projecting upwardly from the receiving end of the conduit where it is operable to cut an opening in the lower end of a container of lubricant forced downwardly on it.

10 19. A device for use on the tubular lubricant receiver of an engine including, a cutter pivoted to the receiver to be shiftable between a position in the receiver and a position projecting from the end of the receiver to open a container 15 brought into engagement with it to have its contents drain into the receiver, and means for holding the cutter against movement when in the last named position.

20. A device for use on the tubular lubricant receiver of an engine including, a cutter shiftable between a position in the receiver and a position projecting from the receiver to open a container brought into contact with it, and releasable means for holding the cutter against movement in the last mentioned position.

21. A can opener attachment for a fluid receiver including, a cutter for piercing a can forced against it and a body carrying the cutter and having a part slidably engaging the upper end 30 portion of the receiver so that the cutter can be varied in position relative to the receiver.

22. A can opener attachment for a fluid receiver including, a cutter for piercing a can forced against it and a body carrying the cutter 35 and having a part slidably engaging the upper end portion of the receiver so that the cutter projects beyond the upper end of the receiver and can be varied in position relative to the receiver.

23. A can opener attachment for a fluid receiver including, a cutter for piercing a can forced against it, a guide related to the cutter to guide a can as it is cut, and a body carrying the cutter and having a part slidably engaging 45 the upper end portion of the receiver so that the cutter can be varied in position relative to the receiver.

OZRO N. WISWELL.
